UNITED STATES PATENT OFFICE.

THYGE NELSEN, OF CHICAGO, ILLINOIS.

ELECTRIC-LAMP FIXTURE.

1,088,165.

Specification of Letters Patent. Patented Feb. 24, 1914.

Application filed August 18, 1913. Serial No. 785,297.

To all whom it may concern:

Be it known that I, THYGE NELSEN, a citizen of the United States, residing at Chicago, in the county of Cook and State of Illinois, have invented certain new and useful Improvements in Electric-Lamp Fixtures, of which the following is a specification.

This invention relates to bracket fixtures for securing electric lamps to a wall or other support, and its object is to provide a fixture of this kind which is simple in construction, which will securely hold the lamp, and which can be easily and cheaply installed. This object is attained by means of a novel combination and arrangement of parts to be hereinafter described and claimed, reference being had to the accompanying drawing, in which—

Figure 1 is an elevation of the fixture, partly in section, and broken away. Fig. 2 is a horizontal section on the line 2—2 of Fig. 1.

Referring specifically to the drawing 10 25 denotes a canopy such as is usually employed in connection with lighting fixtures, said canopy being mounted on a wall 11 or other support in which latter is embedded a stem 12 which projects and has its projecting end screw-threaded. The horizontal arm 13 of a lamp bracket 14 extends centrally through the canopy and is screwed on the projecting end of the stem 12, the latter being located centrally inside the canopy. 30 Set screws 15 threaded through the outer portion of the canopy against the arm 13 secure the canopy in place. The canopy is 35 slideable on the arm, after loosening the set screws, and it is thus adjustable independent of the threaded connection between the arm and the stem 12. The main body of the bracket 14 is a hollow drum of any suitable design having aligned top and bottom openings 16 and 17, respectively. On 40 the top of the bracket, over the opening 16, is mounted a globe and lamp support 18 having an outstanding wide top flange 19 for supporting a globe 20 which incloses the lamp 21. The flange 19 has an upstanding marginal rim 22 which surrounds the base of the globe and carries set screws 23 engageable with said globe for holding the same in place. The globe seats on the

flange 19, and the latter has, adjacent to the rim 22, segmental grooves 24 in the bottom 55 of which are apertures 25 opening through the bottom of the flange. The purpose of the grooves and the apertures is to permit the escape of any water which may get on the flange, especially that which runs down 60 the outer surface of the globe and gets between its base portion and the rim 22.

The support 18 has a downwardly tapered vertical recess 26 to receive the socket 27 of the lamp 21, the latter being an ordinary incandescent lamp. The recess opens through the top of the support and has a top countersink 28. The lower portion of the recess is reduced in diameter and screw-threaded, and opens through the base of 70 the support and is in line with the opening 17. Through the center of the drum passes a stem 29, the upper end of which passes through the opening 16 and is threaded to screw into the lower portion of the recess 75 26. The lower end of the stem extends through the opening 17 and projects therefrom a sufficient distance to hold an ornamental tail piece 30, the latter being screwed on the projecting portion of the stem against 80 the bottom of the bracket body 14. The tail piece therefore serves as a nut to hold the stem 29 in place, and the latter, in turn, holds the support 18.

The socket 27 has a slight downward 85 taper so that it may be tightly wedged in the recess 26, in which it is held against upward displacement by rings 31 and 32. The ring 31 is wedged tightly on the socket by being driven toward the larger end thereof. 90 The ring 32 is located between the ring 31 and a shoulder 33 on the socket, and has apertures to receive screws 34 which are screwed into the bottom of the countersink 28, in which latter the rings seat.

The lamp wires 34 pass through the stem 29, the same being tubular. The arm 13 is also tubular to accommodate the wires, the stem having a side opening 35 through which the wires pass to the arm. The arm 100 has a side opening 36 through which the wires pass to the conduits.

The fixture herein described is simple in construction and cheap to manufacture, and it can be easily and quickly installed. The 105 lamp is securely held in place by the fasten-

ing means described, and the invention effectually serves the purpose for which it is designed.

I claim:

5. 1. A lamp fixture comprising a bracket, a stem extending from the bracket and having a projecting threaded end, a lamp support screwed on the projecting end of the stem, the opposite end of the stem being also 10 threaded and projecting from the corresponding portion of the bracket, and a nut screwed on the last-mentioned end of the stem.
15. 2. A lamp fixture comprising a bracket, a lamp and globe support carried by the bracket, said support having a tapered recess and an outstanding shade supporting flange, said recess being countersunk, a tapered lamp socket seating in the recess, a 20 ring encircling the socket and seating in the countersink, the socket having a shoulder against which the ring abuts, and means for securing the ring in the countersink.
25. 3. A lamp fixture comprising a bracket, a lamp and globe support carried by the bracket, said support having a tapered recess and an outstanding shade supporting flange, said recess being countersunk, a tapered lamp socket seating in the recess, a 30 ring wedged on the socket and seating in the aforesaid countersink, a second ring encircling the socket, the latter having a shoulder between which shoulder and the first mentioned ring the second ring is located, and 35 means for securing the second ring in the countersink.
40. 4. A lamp fixture comprising a bracket, a stem passing through the bracket and projecting from opposite ends thereof, the projecting ends of the stem being threaded, a

lamp support screwed on one of the projecting ends of the stem, and a nut screwed on the other projecting end of the stem against the corresponding end of the bracket.

5. A lamp fixture comprising a bracket, a lamp support carried by the bracket, said support having a tapered recess which is countersunk, a tapered lamp socket seating in the recess, a ring encircling the socket and seating in the countersink, the socket having a shoulder against which the ring abuts, and means for securing the ring in the counter- 45 sink. 60

6. A lamp fixture comprising a bracket, a lamp support carried by the bracket, said support having a tapered recess which is countersunk, a tapered lamp socket seating in the recess, a ring wedged on the socket and seating in the aforesaid countersink, a second ring encircling the socket, the latter 55 having a shoulder, between which shoulder and the first-mentioned ring the second ring is located, and means for securing the second ring in the countersink. 60

7. A lamp fixture comprising a bracket 65 having a hollow body portion and a tubular arm, a tubular stem passing through the body portion of the bracket and having a side opening thereinto, said stem projecting from the ends of the bracket, the projecting 70 ends being threaded, a lamp support secured on one projecting end of the stem, and a nut secured on the other projecting end of the stem.

In testimony whereof I affix my signature 75
in presence of two witnesses.

THYGE NELSEN.
